DESIGN FOR A COMBINED BEAUTICIAN'S TRAY AND SHOULDER SUPPORT

Florence Sommers, Los Angeles, Calif.

Application October 28, 1941, Serial No. 103,929

Term of patent 14 years

To all whom it may concern:

Be it known that I, Florence Sommers, a citizen of the United States, residing at Los Angeles, in the county of Los Angeles and State of California, have invented a new, original, and ornamental Design for a Combined Beautician's Tray and Shoulder Support, of which the following is a specification, reference being had to the accompanying drawing, forming part thereof.

Fig. 1 is a perspective view of a combined beautician's tray and shoulder support embodying my new design;

Fig. 2 is a perspective view of the shoulder support and suction cup shown in Fig. 1; and

Fig. 3 is a perspective view of the tray shown in Fig. 1.

I claim:

The ornamental design for a combined beautician's tray and shoulder support, substantially as shown.

FLORENCE SOMMERS.
